UNITED STATES PATENT OFFICE

WILLIAM G. FOARD, OF KALAMAZOO, MICHIGAN

DESIGN FOR A GOLF PUTTER

Application filed July 16, 1929. Serial No. 32,090. Term of patent 14 years.

To all whom it may concern:

Be it known that I, WILLIAM G. FOARD, a citizen of the United States, residing at Kalamazoo, in the county of Kalamazoo, State of Michigan, have invented a new, original, and ornamental Design for Golf Putters, of which the following is a specification, reference being had to the accompanying drawing, forming part thereof.

Fig. 1 is a front elevation of a golf putter, showing my new design, with the staff and handle shown in a fragmentary manner; Fig. 2 is a fragmentary showing of a rear elevation of the same; and Fig. 3 is a fragmentary edge elevation.

I claim:

The ornamental design for a golf putter, as shown.

WILLIAM G. FOARD.
